TRANSFER ELEMENT AND APPARATUS FOR VARNISHING, PAINTING, OR PRINTING.

Application filed February 18, 1924. Serial No. 693,504.

This invention relates to improvements in transfer element and apparatus for varnishing, painting or printing.

One of the objects of this invention is the production of a transfer element for coating with or transferring varnish, paint, printer's ink or the like, to plates or sheets of suitable material, and the use in such a transfer element of a transfer surface formed of the soft and highly elastic composition employed in printers' inking-rollers, while at the same time permitting such surface composition to be detached and changed or varied to suit varying transfer conditions.

Another object of this invention is to produce a highly efficient transfer roller preferably embodying said conventional soft and highly elastic composition and adapted to coat, paint or print in one continuous operation a series of metal blanks or units embodied in a continuous sheet or plate, and to leave on the blanks uncoated marginal spaces or portions to subsequently enable a more facile soldering of such uncoated margins or edges together.

Another object of this invention is to produce a roller having a transfer surface of said conventional soft and highly elastic ink-transferring composition which may be molded flat and then mounted on a core, and we therefore provide a strong flexible fabric base such as heavy duck canvas and securely fasten on one surface thereof a relatively thin layer of such conventional composition and then securely fasten the fabric carrying such surface layer on the periphery of the roller core.

Another object of this invention is to produce a transfer roller having a surface of said highly efficient conventional composition in which grooves or channels for the purpose hereinabove specified may be readily formed. To this end we have provided a roller-core on which we detachably mount a transfer element comprising a flexible fabric base having a surface composed of a layer of said conventional composition, in which element channels or grooves are formed, the side walls of which are composed of said composition and the bottom of which is said fabric base. The grooved portions of the roller transfer no coating material and therefore cause a large sheet to have uncoated strips, which

strips, when the sheet is cut up into blanks, will form uncoated margins for such blanks, to enable the same to be easily soldered together without, as is necessary when the margin is coated, first stripping off such coating material.

The forming of channels in the layer of composition to provide uncoated margins on the blanks to be severed from coated sheets may be accomplished by placing dividing partitions in the mold for forming the same or by cutting parallel lines in the surface of the composition layer and stripping the portions between such parallel lines from the fabric. It will be obvious that a heavy fabric, such as canvas duck, will form a non-penetrable severing bed on which the composition may be cut and from which it may be stripped without in any way damaging the fabric.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a vertical section showing in separated relationship our preferred devices used for producing a transfer element, being a mold containing a transfer composition, a fabric frame carrying a fabric and a steam chest;

Fig. 2 is a view similar to Fig. 1 showing the elements of Fig. 1 brought together to secure an adherence of the transfer composition to the fabric;

Fig. 3 is a similar view of the elements of Figs. 1 and 2 after the adherence of the composition to the fabric;

Fig. 4 is a fragmentary section of a piece of fabric and composition mounted thereon;

Fig. 5 is a plan view of the apparatus shown in Figs. 1, 2 and 3;

Fig. 6 is a plan view of a transfer element having a series of coating areas separated by grooves or channels formed in the composition to produce on a sheet of metal or the like a series of coated areas separated by uncoated strips;

Fig. 7 is a perspective view of a portion of a mold having partitions adapted to produce grooves or channels shown in Fig. 6; and

Fig. 8 is a fragmentary view of a varnishing machine illustrating a transfer roller having our transfer element mounted thereon in the operation of coating a metal plate.

Referring now to these drawings, which illustrate a preferred embodiment of our invention, 1 (Fig. 4) illustrates a fragment of a transfer element composed of a flexible fabric 2 and a layer 3 of soft, highly elastic transfer composition usually employed in printers' inking rollers. This transfer-composition 15 may be composed of varying ingredients, one of which compositions comprises glue 14 lbs., glycerin 28 lbs., castor oil 2 1/4 lbs., borax 3 ounces, ammonia 2 ounces and sugar 7 lbs. Other compositions are composed of glue and 20 molasses and glue and honey.

According to our invention, the layer 3 of said soft and highly elastic transfer composition is caused to firmly adhere to the surface of the fabric 2 and for this purpose we preferably provide apparatus consisting of a mold 4 having a bed plate 5 provided with a smooth bottom surface 5^a surrounded by frame members 6, which project above the bottom surface 5^a a sufficient distance to provide a suitable thickness for the layer of composition 3, which when melted is poured into said mold. Superimposed upon the mold 4 is the sheet of fabric 2 preferably composed of heavy duck 35 canvas which is of greater length than the mold, so that when a layer of composition is fastened thereto, as hereinafter specified, uncovered ends 2^a—2^b will be provided for the purpose of fastening the same as hereinafter 40 stated. This canvas is preferably stretched in a stretching frame 7 having stationary fastening prongs 8 at one end and a stretching roller 9 at the opposite end having fastening prongs 9^a thereon. The frame with the canvas 45 stretched thereon is placed over the mold 4, so that the under surface of the stretched canvas will contact with the upper surface of the composition 3. A steam-box 10 is then brought down over the fabric and mold 4 and 50 steam to heat the canvas and melt the composition 3 is admitted to conduits 11 in said box through the inlet pipe 12 controlled by valve 13, circulation being established through outlet pipe 14 controlled by valve 15. 55 A portion of the melted composition will thereupon penetrate the canvas 2 and, if the composition be then cooled, a strong adherent union will take place between the composition and the fabric or canvas 2. A quick and effective cooling of the composition is accomplished by shutting off the steam and passing cold water through the conduits 11.

As illustrated, steam may be shut off by the valves 13 and 15 and cold water may be admitted through the water-inlet pipe 16 which

is controlled by the valve 17, circulation being established through the water outlet pipe 18 controlled by the valve 19.

When the composition is cooled by the water the box may be removed in any suitable way. The composition contained in the mold will be found to have strongly adhered to the fabric and the outer surface 2^c thereof, which formerly abutted against the smooth bottom 5^a of the bed plate, will be flat and smooth so as to provide a desirable coating surface which will be free from air-holes or bubbles, as any bubbles or air-holes will form on the upper surface of the molded material which is united to the fabric, as aforesaid, by a strong adherent joint.

It is desirable in one continuous operation to coat with varnish, paint or other suitable coating a sheet of metal having an area sufficient to produce a series of metal blanks and furthermore in one continuous operation to coat a series of these blanks so as to differentiate each blank from its neighbor and also to coat each of the blanks in such a manner as to provide an uncoated soldering area or strip 90 at the margins thereof so that soldering may be accomplished without the usual scraping of coated surfaces. It is desirable to leave such an uncoated strip along all the marginal edges of each blank, and in the preferred embodiment of our invention shown we have provided means for bringing the surface of a sheet of material to be coated of sufficient area to contain a plurality of blanks or units into contact with a transfer surface adapted to 100 produce a series of separated coated areas having uncoated strips completely surrounding each of the coated areas. These sheets may thereafter be served along and within the uncoated strips to produce blanks or units 105 with uncoated margins which may then be soldered without the scraping off of coating material.

To this end we provide, as more particularly shown in Fig. 6, in the layer of composition of the transfer element a series of relatively narrow grooves or channels 3^a which extend from the top smooth surface to the bottom of the fabric base. This grooving or channeling 3^a is preferably accomplished by providing the mold 4 with a series of longitudinal and transverse separating strips or partitions 5^b, though such grooves or channels might be formed by cutting strips out of the composition material. Such a procedure, however, 120 would involve the use of some additional material and labor.

In the preferred embodiment of our invention, a transfer element is mounted (see Fig. 8) upon a roller 20 of conventional form, 125 the ends 2^a—2^b being fastened to fastening spindles 21 of the roller in any suitable manner. Varnish may be fed to the transfer elements on the roller by rollers 22 and 23 which rotate within a trough or tank 24. The metal 130

sheet 25 is fed beneath and held in contact with the roller 20 by a supporting roller 26. Obviously when a roller so formed is used, the plate will be coated to provide a series of 5 isolated or separated areas each comprising a metal blank which will be surrounded by uncoated strips, and upon the severing of these sheets along and within said uncoated strips, individual blanks having uncoated margins 10 will be produced, which blanks may, as aforesaid, be readily soldered without the necessity of scraping off and wasting a portion of the coating.

Having described our invention, we 15 claim:—

1. A transfer roller comprising a substantially cylindrical core, a layer of soft highly-elastic transfer composition mounted on said core and having a surface provided with a 20 series of intercommunicating channels ex-

tending transversely and circumferentially in the outer peripheral surface thereof, said channeled surface being formed of a series of independent blocks spaced from each other and each having a smooth cast printing surface and similar cast edge surfaces. 25

2. A transfer roller comprising a substantially cylindrical core, a layer of soft highly-elastic transfer composition mounted on said core and having a surface provided with a 30 series of intercommunicating channels, said channeled surface being formed of a series of independent surfaces spaced from each other and each having a smooth cast printing surface and similar cast edge surfaces. 35

In witness whereof, we have signed our names to the foregoing specification.

CHARLES WAGNER.
AUGUST HORMEL.
